UNITED STATES PATENT OFFICE.

EDWARD LA VINE, OF BRUSSELS, BELGIUM.

DESIGN FOR A RING.

44,926.

Specification for Design.

Patented Nov. 25, 1913.

Application filed July 21, 1913. Serial No. 780,401. Term of patent 7 years.

To all whom it may concern:

Be it known that I, EDWARD LA VINE, a citizen of the United States of America, residing at Brussels, Belgium, have invented a new, original, and ornamental Design for a Ring, of which the following is a specification, reference being had to the accompanying drawing, forming part thereof.

Figure 1 is a perspective view of the ring; Fig. 2 is a front view and Fig. 3 is a side view thereof.

The ring is, at its front part, constituted by a fork 1 having an ornament at 2 so as to represent the compasses of the insignia of freemasonry. To the extremities of the fork 1 are connected the extremities of a second

fork 3 representing the fork of a chicken breast-bone and constituting the rear part of the ring. On the branches of the fork 1 is, in an appropriate manner, arranged a square 4, the upper side of the ring thus representing the insignia of freemasonry.

I claim—

The ornamental design for a ring, as herein shown and described.

In testimony whereof, I have signed my name to this specification in the presence of two subscribing witnesses.

EDWARD LA VINE.

Witnesses:

MANUEL WOODSON,
C. A. OARDE.
